(57) CLAIM

The ornamental design for a vehicle wheel, toy vehicle wheel, and/or replicas thereof, as shown and described.

DESCRIPTION

FIG. 1 is a perspective view of a vehicle wheel, toy vehicle wheel, and/or replicas thereof according to the design;
FIG. 2 is an additional perspective view thereof;
FIG. 3 is an additional perspective view thereof;
FIG. 4 is a front view thereof;
FIG. 5 is a rear view thereof; and,
FIG. 6 is a side view thereof.
FIG. 5 is shown in low-contrast rendering to depict environmental subject matter and forms no part of the claim.
